TOY WAGON

Frank F. Voorheis, Downers Grove, Ill.

Application May 20, 1939, Serial No. 274,777

1 Claim. (Cl. 280—100)

My invention relates to toy wagons.

Among the objects of my invention is to provide toy wagons having a construction that will permit them to turn in the minimum of space and in which the second unit will follow exactly in line with the path of the first unit, and such other objects, advantages and capabilities as will later more fully appear and which are inherently possessed by my invention.

10 While I have shown in the accompanying drawing a preferred form of my invention yet I desire it understood that the same is susceptible of modification and change without departing from the spirit of my invention.

15 Referring to the drawing Fig. 1 is a top plan view of a pair of my toy wagons; Fig. 2 is a side elevation of one of my wagons; Fig. 3 is a top plan view on line 3—3 of Fig. 2, and Fig. 4 is an end elevation of my toy wagon.

20 The embodiment selected to illustrate my invention comprises a wagon 16 having the usual floor 11 and walls 12. Adjacent each of the ends of the wagon is a block 13 attached to the under portion of the floor 11 by suitable means such as 25 screws or the like.

In each of said blocks 13 the upper end of a bolt 14 is positioned. Each of said bolts continues downwardly through a bushing 15 in axle frame 16. The bottom of each bolt 14 may have a nut 30 or head 17. A nut 18 is placed on each bolt just above where it enters the block 13.

35 Each axle frame 16 is substantially U shaped with wide arm portions 19 joined by a connecting portion 20 and having a hollowed out central portion 21. Through the arms 19 and hollow central portion 21 of each of said axle frames 16 extends an axle 22 which supports wheels 23.

40 A rod or shaft 24 is attached on one end to one of the axle frames 16 and on the other end to the other axle frame. Preferably, the ends of the rod are attached to flattened top 26 of the axle frame 16 at the opposite inner edges of the ends of the same, as shown in Fig. 3 at 26 and 27. One end of the rod 24 is attached as far 45 laterally from the center of one axle frame, as the

other end is attached to the other axle frame 16.

The axle frames 16 pivot on bolts 14 to about 45 degrees and are prevented from further pivoting by block 28 attached to the bottom of floor 11 at the rear end thereof.

5 A tongue 29 is attached to the front of axle frame 16. Loops 30 are attached to tongue 29 and loops 31 to receive a connecting bolt or like 32 so that several wagons or a trailer may be attached thereto.

10 In use, when the front wheels of one of my wagons are turned, the rod 24 also acts to turn the rear wheels. This permits turning in a minimum of space. Connected wagons attached to the front wagon follow in the same path as the 15 wheels of the front wagon.

Having thus described my invention, I claim:

A toy wagon comprising a body portion, a pair of blocks attached to the under portion of the floor of the wagon at opposite ends thereof, a pair 20 of axle frames pivotally attached to said blocks, said axle frames substantially U shaped and having a pair of arms, a connecting portion, a central hollow portion and a flat top, a pair of axles attached to said axle frames and extending 25 through the arms and hollow portions of the same, wheels supported on said axles, a connecting bar extending between said axle frames, one end of said bar attached to the flat top of one of said axle frames a desired distance laterally of 30 the center in one direction, and the other end of the bar attached to the flat top of the other of said axle frames a desired distance laterally of 35 the center in the direction opposite to the first mentioned axle frame so that when the front 40 wheels are turned the connecting bar will cause the rear wheels to also turn so that the wagon may be turned in a minimum of space, and a stop member attached to the bottom side of the rear of the floor of the wagon to engage the axle frame upon movement past 45 degrees, and means attached to said stop member for engaging another wagon or trailer.

FRANK F. VOORHEIS. 45
